Specification of Letters Patent.

Patented Oct. 21, 1913.

Application filed March 4, 1910. Serial No. 547,379.

To all whom it may concern:

Be it known that I, MITTS QUENNER, a citizen of the United States, residing at Santa Ana, Sonora, Mexico, have invented 5 certain new and useful Improvements in Ore-Treating Machines, of which the following is a specification, reference being had therein to the accompanying drawing.

This invention relates to a machine for 10 breaking up material such as rock, coal and other substances and has for its primary object the provision of instrumentalities for expeditiously and effectively accomplishing the result stated.

15 Heretofore in the art of reduction, especially that branch of the art which deals with the reduction of masses of stone, coal or other lump substances, it has been usual to subject the material to the crushing action of rolls, jaws, stamps or hammers, all 20 of which require the material to be backed up or supported so that the crushing force will be directed against the material and resisted in the main by the backing or supports.

In the use of machines designed to assist in carrying into practical effect the art above referred to, there has been the inherent production of a very considerable amount of 25 pyritic or fine material which though desirable in some instances is absolutely useless in others. For example, in breaking coal, to reduce the size to the proportions required for use, and when breaking rock to 30 reduce the size to the proper proportions, as in the product known as "road ballast" it is very desirable to avoid, so far as possible, any crushing action of the stone or coal and thus substantially eliminate the production 35 of "fines" and "culm." It is the foregoing condition of the reduction art that is met and improved upon by a new method of 40 breaking or shattering the rock, coal, etc., devised by me and by my improved machine 45 constituting the subject matter hereof, designed especially for use to facilitate the carrying of said method into practical effect.

Generally speaking, as distinguished from a crusher or grinding machine, the principal 50 characteristic of my present machine is its breaking or shattering operation.

I have illustrated in the accompanying drawings the preferred embodiment of my invention, although it will be noted by those 55 skilled in the art that the invention is capa-

ble of embodiment in still other forms and arrangements.

Features of the above mentioned machine are the provision of breaking or shattering instrumentalities comprising a rotatable shaft and a plurality of flexibly mounted projectiles arranged to strike and shatter the rock and conveniently disposed to cause the material being treated to travel from the inlet to the discharge end of the machine; and 60 more particularly said flexibly hung projectiles arranged within a cylindrical co-operating member, preferably a grizzly, and the projectiles mounted in spiral arrangement on the operating shaft so that under their 65 rapid rotation they create the desired feeding or traveling movement of the material somewhat after the manner of an ordinary 70 screw conveyer.

Still other features are means for closing 75 the discharge end of the cylinder or grizzly and for regulating the discharge of material through said end, said regulating means being preferably adjustable; means for adjusting the grizzly to regulate the size of 80 the escape passages therethrough; means for effecting rotation of the projectiles and grizzly in the same direction but at differing 85 speeds; and a relative arrangement of the feed and discharge openings at the opposite 90 ends of the grizzly tending to cause the material to travel an approximately inclined 95 path from the inlet to the outlet to assist the feeding or traveling movement of the material under the influence of the spirally 100 arranged beaters.

All of the foregoing as well as other novel details in the construction and arrangement of the parts of my machine will be apparent from the detailed description hereinafter 105 contained, when read in connection with the accompanying drawings forming part hereof and wherein a convenient embodiment of the invention is illustrated. It is to be understood, however, that although I have, for the sake of imparting a full understanding of my invention, illustrated a special embodiment thereof, the invention is capable of embodiment in other forms and devices than that disclosed herein without departing 110 from the spirit of my invention.

In the drawings, Figure 1 is a side elevation of the machine, Fig. 2 is an end view looking in the direction of the arrow, Fig. 1, Fig. 3 is an opposite end view, Fig. 4 is a

longitudinal sectional view of Fig. 1, Fig. 5 is a transverse sectional view through Fig. 1 looking toward the feed end of the machine, Fig. 6 is a detail perspective view of a fragmentary portion of the projectile shaft and the projectiles flexibly connected thereto, Fig. 7 is a detail perspective view of one of the projectiles, Fig. 8 is a vertical sectional view through the discharge end of the machine, and Fig. 9 is a detail section through a peripheral portion of the grizzly showing the manner of adjustably connecting the slats to the ends or heads of the grizzly.

Referring more specifically to the drawings wherein like reference characters designate corresponding portions in the several views, A represents the base of the supporting frame formed in any suitable manner and of any suitable material, that shown being composed of heavy wooden beams provided with three laterally braced upright portions B carrying at their upper ends suitable bearings C in which a rotatable beater shaft D works. Auxiliary somewhat shorter supports E arranged adjacent to the supports B and supporting on their upper surfaces bearings F rotatably support a pair of parallel shafts G carrying properly spaced opposite pairs of flanged wheels, H. Drive pulleys d and g are respectively secured to the shafts D and G, for the purpose of rotating these shafts through the medium of belts d', g' running from pulleys d'', g'' on a driven shaft I receiving its power from any suitable source not necessary to herein further refer to. It is to be noted, however, that by the arrangement just described the shafts D and G are rotated in the same direction and that, owing to the relative arrangements and size of the power transmitting means, the shaft D will be rotated at a much greater speed than the speed of rotation of the shaft G, for a purpose as will presently appear.

J represents a grizzly provided at its opposite ends with outwardly projecting supporting flanges h adapted to rest upon the peripheries of the flanged wheels H, as clearly shown in Figs. 1 and 2, it being here observed that the wheels H constitute the only means of supporting the grizzly, the latter being held in place by its own weight and the weight of the material being treated therein, the respective pairs of wheels being separated to afford a firm seating for the grizzly preventing any tendency of the same to become displaced in a lateral direction, and the flanges of the wheels H engaging the outer edges of the flanges h of the grizzly preventing any endwise movement thereof. The grizzly is provided with ends or heads j (Fig. 4) having circumferentially slotted inturned flanges j' for detachably securing the slats K in place, the ends of the slats being similarly slotted, as at k (Fig.

9) to permit an adjustment of the same, bolts and nuts k' securing the slats in position, as desired.

Dependent upon the use to which the machine is to be put, the slats may be adjusted to regulate the spaces between the same through which the broken material will pass, which adjustment, at times, may contemplate the complete closing of the said spaces to afford a practically solid or continuous wall. In Fig. 5, it will be seen that a number of the slats K, designated at K' are quite wide relative to the other slats which are intermediate thereof. These wide slats K' are fixed to the heads j and constitute with said heads what may be termed the frame of the grizzly. In adjusting the grizzly, only those narrow slats between the broad slats K' are shifted, thus facilitating the quick adjustment of the parts from opposite sides of the grizzly, it being observed that when the slats are arranged in close proximity to each other with relatively fine passages therebetween, an additional slat may be inserted between the end narrow slat and the adjacent wide slat K', which said additional slat is removed when the narrow slats are positioned at correspondingly wider distances apart.

The frictional engagement between the grizzly and the flanged wheels H is sufficient to enable the grizzly to be rotated under the actuation of the driven wheels H on one of the shafts G, as hereinabove set forth, the heads j being open for quite an extent around the shaft D to permit the grizzly to rise and fall in keeping with the wheels H to constantly preserve a firm contact therebetween.

Upon the shaft D and arranged within the grizzly is a multitude of projectiles P. Two-part collars L adapted to embrace and be bound in position upon the shaft D by binding bolts and nuts M secure the same in place. The two parts of the collar are of such form that the ends thereof when drawn toward each other by the bolts and nuts M will not engage, but will leave a space N therebetween for the introduction of the end link of a chain or flexible connection O, whereby the bolt M may also constitute the immediate fastening means for the flexible connection, the arrangement being such that the link which engages the bolt may play freely thereon. The projectiles are preferably formed of steel of rectangular cross section mounted so that in operation one of the sharp edges thereof is presented forwardly, thus enabling the projectile to be reversed at will. Here it may also be observed that in operation the projectile will wear down in time, but they may be used for practically their full length, it simply being necessary to introduce another link in the chain to accommodate for such wearing.

away. Normally the projectiles terminate at a point short of the inside of the grizzly so as not to engage and unduly cut or wear the bars of which the grizzly is formed. In 5 Fig. 6 it is clearly seen that two of the flexibly mounted projectiles are secured to each of the collars, and a highly important feature of the relative arrangements of the successive pairs of projectiles is the fact that 10 they occupy a progressively slightly advancing relation to each other so that the resultant action of the projectiles is substantially that of a spiral, which in operation under the rotation of the shaft causes the 15 projectiles to act somewhat after the manner of a feed screw to effect the travel of the material being treated from the feed end of the machine to the discharge end of the same. Of course the projectiles are 20 thrown outwardly into their operating position and relation by centrifugal action incident to the rotation of the shaft D as hereinbefore pointed out. While the projectiles are thus thrown out by centrifugal 25 force they are held to a normally circular path of movement by their flexible connection with the shaft D. It is to be observed, however, that the said connection represents largely a tether confining the projectiles to 30 movements within certain limits. This is important in that when the projectiles strike the material no destructive vibrations are transmitted to the shaft. Again there is practically no impediment to the continued movement of the projectiles after 35 the blow has been delivered, the movement of the shaft drawing the projectiles around the rock or portions which may be in the path of the projectiles after impact. Should 40 the impact be delivered or resisted at a point between the projectile and the shaft, the result would be that the projectile would be drawn down by its momentive force onto a portion of the rock, the blow 45 being in the direction toward approximately the center of the grizzly. This tethering of the projectiles enables the machine to be run at a very high rate of speed so that effective blows can be delivered rapidly on the obstructing material and thus quickly shatter 50 and break up the lumps or rock.

Q is a feed hopper leading to an opening q in the adjacent head of the grizzly, the hopper being mounted upon a bracket q' to 55 be held stationary at all times.

R is a flaring flange carried by the discharge head or end of the grizzly and secured thereto so that it rotates with the grizzly, this flange being arranged to serve 60 at all times as an inclined conducting surface to guide the material discharged from the grizzly J to a stationary inclined grizzly S discharging to any suitable auxiliary treating machinery or to any point desired. The discharge opening T of the grizzly is of some-

what greater diameter than the inlet opening g, as is indicated in Fig. 4, so that the material being treated tends to traverse an incline approximately on the dotted line t from the inlet to the outlet, which will assist the beaters in effecting the desired feed of the material. 70

U is a door or closing plate for the discharge opening T, the same being sleeved upon the projectile shaft D and held in fixed position and free from rotation with the grizzly by a bracket u projecting inwardly from the adjacent upright portion B of the frame. The lower portion of the plate U is divided horizontally and hinged along the 75 line of its division as at v, to constitute a hinged flap or door V, the same being normally held in closed position through the medium of an adjustable spring retaining device W supported from a bracket w on said upright portion B. It will be obvious that by adjusting the nut of this spring device, the flap or door V will open or close with greater or less pressure from the interior of the grizzly as the case may be. 80

X are deflecting plates arranged parallel to the axis of the grizzly and adapted to guide substances escaping from the upper portion of the grizzly down to the ground or into suitable receptacles at the base of 85 the same. 90

From the foregoing description, the operation of the machine may now be followed. The operating medium being applied to rotate them, the pulleys d'' and g'' will, 100 through the medium of their respective belts, d', g' rotate the pulleys d and g, thus effecting rotation of the projectile shaft D and one of the shafts g with the pair of flanged wheels H thereon. The grizzly 105 bearing upon said wheels will be correspondingly rotated, tending to move, carry upwardly or turn over, at relatively slow speed, the material introduced through the hopper Q. The flexible projectiles on the 110 shaft D will be rotated in the same direction but under a relatively high speed to combat the material in the grizzly and break the same up, as desired, the centrifugal action 115 extending all the projectiles and the spiral arrangement of the projectiles imparting the desired feeding movement to the shattered or broken material from one end of the machine to the other. The machine will accommodate material of any size which may 120 be fed thereinto, and as the material is delivered to the machine, the grizzly having attained its relatively slow rotation and the projectiles their correspondingly high rate of movement in the same direction, the material is struck repeatedly and shattered by 125 impact blows delivered in a direction slightly tangent to the walls of the grizzly. The unshattered parts are subjected to repeated blows projecting the rock forward 130

against other moving bodies of rock and this continuous action of rapidly repeated impact projectile blows soon shatters the rock without effecting any material or substantial crushing or pulverizing thereof. As the rock particles become shattered or broken to a size which will permit them to escape through the openings between the slats they are gathered below the machine or may be fed to any suitable receptacle or separator. The advance or moving or turning over of the material by the grizzly or cage prevents the material from assuming a condition of rest and thus a backing which might otherwise be present is substantially avoided, this insuring the material being treated in what may be termed a floating free or moving condition. Any of the fine or lighter particles of the material escaping from the upper portion of the grizzly or the sides thereof are deflected downwardly by the deflecting side plates X, as before noted. The size of the material is regulated by the adjustment of the escape passages between the slats of the grizzly and by the speed of rotation of the projectiles. Owing to this adjustable characteristic of the machine both respecting arrangement of parts and relative speeds of movement, the machine is capable of use in various instances other than that use for which the invention was primarily designed, to wit, as a breaking and shattering mechanism for rock, etc. For example by firmly closing the door V to practically prevent escape of material, the machine may be used purely as a crusher or pulverizer, reducing all of the material introduced thereto to a given degree of fineness determined by the escape passages through the slats of the grizzly. Further, the machinery may be used as a mill or mixer by practically closing the slatted periphery of the grizzly together, to form a substantially continuous solid wall when the material will be treated by the projectiles and gradually fed in its entirety through the flap or door V.

I mention the foregoing matters to illustrate the various uses to which the machine may be put; the same having been found efficacious in all of the particulars noted.

I will not claim herein specifically the subsidiary part or sub-combination of my invention involving broadly the rotatable grizzly and the special means for closing the discharge opening thereof inasmuch as the same more properly constitutes subject matter for a divisional application.

I claim:

60 1. In a machine for shattering rock, coal and other material, the combination with a shaft and means for driving the same at a high rate of speed, shattering projectiles having sharp longitudinal edges, a series of links constituting substantially universal

connections between the projectiles and the shaft, and a surrounding member into which the material to be treated is introduced toward and from which the projectiles may be adjusted by means of the link connections, 70 said projectiles comprising elongated members of angular cross section arranged to present one of their sharp longitudinal edges in the direction of movement of the projectiles. 75

2. A projectile of the character described provided with an angular longitudinally disposed relatively sharp forward edge and lateral and rearwardly extending enlargements behind said edge. 80

3. A projectile or hammer for a crushing or shattering mill provided with angular longitudinally disposed relatively sharp forward and rear edges, and laterally projecting enlargements behind said edges reinforcing the same. 85

4. A rock breaker of the character described comprising a surrounding grizzly and a plurality of oppositely disposed distinct series of projectiles, in combination with means for rotating the projectiles, substantially as described. 90

5. A rock breaker of the character described comprising a surrounding grizzly and oppositely disposed distinct series of 95 projectiles, in combination with means for rotating the projectiles, and means for rotating the grizzly.

6. A rock breaker of the character described comprising a cylindrical grizzly and a plurality of oppositely disposed distinct series of projectiles, in combination with means for rotating the projectiles, substantially as described. 100

7. A rock breaker of the character described comprising a cylindrical grizzly and oppositely disposed distinct series of projectiles, in combination with means for rotating the projectiles and means for rotating the grizzly. 105

8. A rock breaker of the character described comprising a cylindrical grizzly and a plurality of oppositely disposed distinct series of projectiles, in combination with means for rotating the projectiles, and 115 means for rotating the grizzly in the same direction as the rotation of the projectiles and at relatively slower speed.

9. In a machine for shattering rock, coal and other material, the combination with a substantially horizontally disposed shaft, of means for driving the same at a high rate of speed, shattering projectiles; means for securing the projectiles to the shaft to permit substantially universal free and independent movement of the projectiles in divers directions and paths, and a surrounding member into which the material to be treated is introduced, the same being arranged out of contact with the projectiles 120 125 130

- but in juxtaposition thereto circumferentially of and throughout the said member for maintaining the material in position to be acted on by the projectiles throughout the movement of said projectiles.
10. In a machine for shattering rock, coal and other material, the combination with a shaft and means for driving the same at a high rate of speed, shattering projectiles, substantially universally flexible restraining devices carrying the projectiles at their outer ends and in turn connected to the shaft, a rotatable surrounding member into which the material to be treated is introduced, the same being arranged out of contact with the projectiles but in juxtaposition thereto for maintaining the material in position to be acted on by the projectiles throughout the active zone of operation of said projectiles, and means for rotating the said surrounding member.
11. In a machine for shattering rock, coal and other material, the combination with a shaft and means for driving the same at a high rate of speed, shattering projectiles, substantially universally flexible restraining devices carrying the projectiles at their outer ends and in turn connected to the shaft, and a surrounding member into which the material to be treated is introduced, the same being arranged out of contact with the projectiles but in juxtaposition thereto for maintaining the material in position to be acted on by the projectiles throughout the active zone of operation of said projectiles.
12. In a machine for shattering rock, coal and other material, a series of shattering projectiles, means for driving the same at a high rate of speed, substantially universally flexible restraining devices carrying the projectiles at one end thereof and in turn connected to said driving means, and a rotatable surrounding member into which the material to be treated is introduced, the same maintaining the material in position to be acted on by the projectiles throughout the active zone of operation of said projectiles.
13. In a machine for shattering rock, coal and other material, the combination with a shaft and means for driving the same at a high rate of speed, shattering projectiles, substantially universally flexible restraining devices carrying the projectiles at their outer ends and in turn connected to the shaft, and a rotatable cylindrical surrounding member into which the material to be treated is introduced, the same being arranged out of contact with the projectiles but in juxtaposition thereto for maintaining the material in position to be acted on by the projectiles throughout the active zone of operation of said projectiles, and means for rotating the cylindrical member.
14. In a machine for shattering rock, coal and other material, the combination with a shaft and means for driving the same at a high rate of speed, shattering projectiles, substantially universally flexible restraining devices carrying the projectiles at their outer ends and in turn connected to the shaft, a rotatable cylindrical surrounding member into which the material to be treated is introduced, the same being arranged out of contact with the projectiles but in juxtaposition thereto for maintaining the material in position to be acted on by the projectiles throughout the active zone of operation of said projectiles, the surrounding member having an inlet at one end and an outlet at its opposite end, and the projectiles being arranged in approximately spiral formation tending to feed the material toward the outlet end of the machine.
15. In a machine for shattering rock, coal and other material, the combination with a shaft and means for driving the same at a high rate of speed, shattering projectiles, substantially universally flexible restraining devices carrying the projectiles at their outer ends and in turn connected to the shaft, and a cylindrical surrounding member into which the material to be treated is introduced, the same being arranged out of contact with the projectiles but in juxtaposition thereto for maintaining the material in position to be acted on by the projectiles throughout the active zone of operation of said projectiles.
16. In a machine for shattering rock, coal and other material, a series of shattering projectiles, means for driving the same at a high rate of speed, and substantially universally flexible restraining devices carrying the projectiles at one end thereof and in turn connected to said driving means, the machine including a rotatable cylindrical surrounding member into which the material to be treated is introduced, the same maintaining the material in position to be acted on by the projectiles throughout the active zone of operation of said projectiles.
17. In a machine for shattering rock, coal and other material, the combination with a shaft and means for driving the same at a high rate of speed, shattering projectiles, a series of links constituting substantially universally flexible connections between the projectiles and the shaft, and a surrounding member into which the material to be treated is introduced, said projectiles comprising elongated members of substantially uniform angular cross section arranged to present one of their sharp longitudinal edges in the direction of movement of the projectiles.
18. In a machine for shattering rock, coal and other material, the combination with a shaft and means for driving the same at a high rate of speed, shattering projectiles,

- substantially universally flexible restraining devices carrying the projectiles at their outer ends and in turn connected to the shaft, and a surrounding member into which the material to be treated is introduced, the same being arranged out of contact with the projectiles but in juxtaposition thereto for maintaining the material in position to be acted on by the projectiles throughout the movement of the latter, said projectiles being arranged in stepped relation to successively combat the material presented from the forward to the following projectiles in its course of treatment in the machine.

15 19. In a machine for shattering rock, coal and other material, the combination with a shaft and means for driving the same at a high rate of speed, shattering projectiles, substantially universally flexible restraining devices carrying the projectiles at their outer ends and in turn connected to the shaft, a rotatable cylindrical surrounding member into which the material to be treated is introduced, the same being arranged out of contact with the projectiles but in juxtaposition thereto for maintaining the material in position to be acted on by the projectiles throughout the active zone of operation of said projectiles, an inlet in one end of the surrounding member, peripheral and end discharges therefrom, and independent means for adjusting and centering the peripheral and end discharges, substantially as described.

30 20. In a machine for shattering rock, coal and other material, the combination with shattering means, a rotatable cylindrical member surrounding the same into which the material to be treated is introduced, said cylindrical member comprising oppositely disposed heads widely spaced relatively permanent members connecting said heads together, and constituting intermediate peripheral slats, and other slats constituting the remainder of the periphery of said member adjustably connected to the heads to be moved toward and from said permanent slats, substantially as and for the purpose described.

45 21. In a machine for shattering rock, coal and other material, shattering mechanism, a rotatable cylindrical member surrounding the same into which the material to be treated is introduced, a discharge opening at one end of said cylindrical member, an outwardly flaring continuous ring bordering and projecting outwardly from said discharge opening carried by and rotatable

50 with the cylindrical member adapted to present at all times a discharge spout at the base of said discharge opening, and a yieldable closure within said flaring ring covering the discharge opening from the cylindrical member, substantially as described.

55 22. In a machine for shattering rock, coal and other material, shattering mechanism, a rotatable cylindrical member surrounding the same into which the material to be treated is introduced, a discharge opening at one end of said cylindrical member, an outwardly flaring continuous ring bordering and projecting outwardly from said discharge opening carried by and rotatable

60 with the cylindrical member adapted to present at all times a discharge spout at the base of said discharge opening, a yieldable closure within said flaring ring covering the discharge opening from the cylindrical member, said yieldable closure comprising a plate bridging the inner open end of said flaring ring held against rotation with respect to the same, and an adjustable automatically actuable flap constituting a part of said plate located at the lower portion of the opening.

65 23. In a machine for shattering rock, coal and other material, the combination of shattering means, a rotatable cylindrical surrounding member therefor into which the material to be treated is introduced, said member having a discharge opening at one end, and means for closing said opening comprising a plate fitting the same but held against rotation with the cylindrical member, said member being provided with an outwardly extending funnel portion rotatable therewith, and surrounding said plate, substantially as described.

70 24. In a machine for shattering rock, coal and other material, the combination of shattering means, a rigid tubular surrounding member therefor into which the material to be treated is introduced, said member having a discharge opening, and means for closing said opening comprising a plate fitting the same but held against rotation with the tubular member, said member being provided with an outwardly extending funnel portion rigidly therewith and surrounding said plate, substantially as described.

75 It is testimony whereof I affix my signature in presence of two witnesses:

W. H. COOPER,
THOMAS RICHARDSON.
